STATIONERY PADDING DEVICE

Clark W. Bond, Littleton, Colo.

Application April 8, 1942, Serial No. 438,192

2 Claims. (Cl. 11-1)

This invention relates to padding devices of that general class shown and described in United States Letters Patent No. 1,763,749, issued to me on the 17th day of June, 1930, the present invention being an improvement thereon.

The object of the invention is generally to improve and simplify the construction of the device and to increase its utility and efficiency by pivotally mounting the presser feet on the adjustable standards whereby to cause said feet to exert an even downward pressure on the sheets of paper during the gluing operation, regardless of the position of said standards with respect to the table or bench.

A further object of the invention is to cheapen the construction and lighten the weight of the device by forming the component parts thereof of wood instead of metal and further to provide a novel corner anchorage for each end of the supporting frame and novel means for securing said frame in position on the bench.

Further objects and advantages will appear in the following specification, in which Figure 1 is a front view of the device, Figure 2 is a top plan view thereof, Figure 3 is a bottom view, Figure 4 is an end view partly in section, Figure 5 is a vertical sectional view taken on the line 5-5 of Figure 1,

Figure 6 is a perspective view of one of the adjustable standards and its presser foot, the parts being shown separated for the purpose of clearness,

Figure 7 is a transverse sectional view taken on the line 7-7 of Figure 2, and

Figure 8 is a detail perspective view showing the manner of connecting and anchoring the corners of the supporting frame.

The improved padding device forming the subject-matter of the present invention comprises a supporting frame consisting of a horizontal bar 5 having its lower longitudinal edge at the opposite ends of the bar cut away to form recesses 6 having relatively shallow side grooves 7 communicating therewith and adapted to receive the slotted ends 8 of vertical arms 9, the parts being secured in position by means of bolts 10 extending through the slotted ends of the arms 9 and through openings 11 formed in the grooved ends of the horizontal bar, as best shown in Figures 1 and 8 of the drawings. The lower ends of the vertical arms 9 are rabbeted at 12 and seated in the rabbeted portions 12 of the arms and secured thereto by screws 13 are attaching blocks 14. The blocks 14 are adapted

to rest on the upper surface of a table, bench or other suitable support 15, said blocks being secured thereto by means of screws 16 countersunk in the opposite inclined edges 17 of the blocks and preferably disposed at an angle to each other, as shown.

Disposed between the vertical arms 9 are a plurality of vertically adjustable standards 18, preferably three in number, although four or five of said standards may be employed if desired. The supporting frame as well as the standards 18 are preferably constructed of wood so as to cheapen the construction and lighten the weight of the device, but it is not desired to limit the invention to any particular kind of material. The standards 18 are provided with longitudinally disposed slots 19 and extending through said slots are clamping bolts 20, the heads 21 of which bear against the horizontal bar 5 while the threaded ends thereof engage clamping nuts 22 whereby to hold the standards in different positions of vertical adjustment. The bolts 20 also act as pivots for the standards when it is desired to swing said standards laterally under certain conditions, as will be more fully explained hereinafter.

Associated with each standard 18 is a presser foot 23 consisting of an elongated block having its front side beveled at 24 to assist in preventing glue inadvertently getting thereon, said block being provided with a centrally disposed opening 25 extending entirely through the block and having its opposite end walls upwardly beveled at 26 to form stop shoulders. The lower face of each presser foot is preferably cut away at 27 to form a clearance communication with the opening 25 and seated in said opening is the lower end of the adjacent standard 18, the parts being pivotally connected by means of a pin 28 extending partially through the presser foot and entirely through said standard so as to permit lateral tilting movement of the presser foot to exert a uniform downward pressure on the sheets of paper, indicated at 29. The lower end 40 of each standard 18 is inclined downwardly to form converging side edges 30 which by engagement with the stop shoulders 26, serve to limit the lateral tilting movement of the presser foot.

In using the device, the sheets of paper 29 are stacked one upon the other on the bench 15 and the standard 18 moved downwardly so as to cause the presser foot to bear against the sheets of paper and in which position it will be held by tightening the nut 22 so as to prevent accidental displacement of said sheets of paper

when applying glue or other adhesive material on one or more of the edges of the strips to form a tablet or pad. Should the sheets of paper 29 be too long or too wide to fit beneath one of the presser feet and not long or wide enough to fit beneath two of said presser feet when the standards are in vertical position, said sheets of paper may be firmly clamped in position on the bench during the gluing operation by loosening the clamping nuts 22 on adjacent standards and swinging said standards laterally on the frame toward each other, with the bolts 20 as a pivot, until the lower ends of the presser feet engage said sheets of paper and then tightening said clamping nuts. Owing to the pivotal connection between the presser feet and the standards, said presser feet will always remain in a horizontal position for clamping action on the sheets of paper regardless of the angle or inclination of the standards with respect to the horizontal supporting bar. By removing the several fastening bolts the component parts of the device may be readily detached and compactly folded for transportation or shipment.

It will, of course, be understood that the devices may be made in different sizes and shapes and provided with any desired number of presser feet without departing from the spirit of the invention.

Having thus described the invention, what is claimed as new is:

1. A device of the class described comprising a frame for attachment to a support, a longitudinally slotted standard mounted for vertical

movement on the frame and having its lower end beveled to form downwardly converging edges, a presser foot having one side thereof provided with a downwardly beveled edge and having its central portion formed with an opening within which the beveled end of the standard is fitted, and a bolt forming a pivotal connection between the presser foot and standard, the opposite end walls of the opening in the presser foot being upwardly beveled and constituting stops for engagement with the beveled edges of said standard to limit the tilting movement of the presser foot with respect thereto.

2. A device of the class described comprising a frame for attachment to a support, a longitudinally slotted standard mounted for vertical adjustment on the frame and having its opposite longitudinal edges at the lower end thereof downwardly inclined, a presser foot having an opening formed therein receiving the inclined end of the standard and having its lower portion cut away to form a clearance communicating with said opening, a bolt extending through the inclined end of the standard and said presser foot and constituting a pivotal connection between the parts, and a clamping member extending through the slot in the standard and engaging the frame for holding the standard in a selected position of vertical adjustment, the opposite end walls of the opening in the presser foot being downwardly beveled to form inclined stops for engagement with the inclined edges of the standard.

CLARK W. BOND.
